UNITED STATES PATENT OFFICE.

JOHN K. ROGERS, OF BROOKLINE, MASSACHUSETTS.

DESIGN FOR TYPE.

SPECIFICATION forming part of Design No. 13,196, dated August 15, 1882.

Application filed March 16, 1882. Term of patent 14 years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing this font consist of an alphabet of script or writing-hand capitals, as

shown in the accompanying impression, taken from the types themselves, and showing their exact forms and outline.

I claim—

The design for types, as described and shown. 15

JOHN K. ROGERS.
